UNITED STATES PATENT OFFICE.

BARRY IVOR, OF CHICAGO, ILLINOIS.

DESIGN FOR A LUBRICATOR-PUMP BODY.

SPECIFICATION forming part of Design No. 33,747, dated December 18, 1900.

Application filed November 23, 1900. Serial No. 37,545. Term of patent 7 years.

To all whom it may concern:

Be it known that I, BARRY IVOR, a citizen of the United States, residing at Chicago, in the county of Cook and State of Illinois, have invented and produced a new and original Design for Lubricator-Pump Bodies, of which the following is a specification, reference being had to the accompanying drawings, forming part thereof.

- Figure 1 is a perspective view of a pump-body, showing my new design; and Fig. 2 is a similar view of the opposite portion.

As shown in the drawings, the leading or material feature of my design consists of a cylindrical portion A, having in its wall a circular opening *a* and mounted on a semi-spherical portion B, which portion is supported by a cylindrical part C, resting on a flat circular base D. The portion B is provided with rectangular openings *b* and *b'*, diagonally opposite each other, and has a vertical flattened portion *b*², provided with a circular

opening *b*³ at about its middle. The upper part of the portion A is formed with annular beads *a'* and has in its top two openings *a*² and *a*³, the latter being much smaller than the former. The top of the portion A is also provided with a raised portion *a*⁴, which is circular in shape. The cylindrical part C is provided with an enlargement *c*, having a circular opening *c'* in its end.

Having described my invention, what I claim as new, and desire to secure by Letters Patent, is—

The design for a lubricator-pump body, substantially as herein shown and described.

In testimony whereof I have signed my name to this specification in the presence of two subscribing witnesses.

BARRY IVOR.
